UNITED STATES PATENT OFFICE.

GILFORD FLEWWELLING AND GILBERT J. HARRIS, OF HAMPTON, NEW BRUNSWICK, CANADA.

MATCH-SPLINT MACHINE.

SPECIFICATION forming part of Letters Patent No. 322,706, dated July 21, 1885.

Application filed April 15, 1885. (No model.)

To all whom it may concern:

Be it known that we, GILFORD FLEWWELLING and GILBERT J. HARRIS, subjects of the Queen of Great Britain, and residents at 5 Hampton, in the county of Kings and Province of New Brunswick, Canada, have invented certain new and useful Improvements in Machines for Making Match-Splints; and we do declare the following to be a full, clear, and 10 exact description of the invention, such as will enable others skilled in the art to which it appertains to make and use the same, reference being had to the accompanying drawings, and to letters or figures of reference marked 15 thereon, which form a part of this specification.

Figure 1 of the drawings is a front view. Fig. 2 is a top view of sliding plate. Fig. 3 is a section of sliding plate. Fig. 4 is a section 20 in detail.

This invention has relation to the manufacture of matches; and it consists in the combination and novel arrangement of devices, all as hereinafter set forth, and pointed out in the 25 appended claims.

The object of the invention is to facilitate the manufacture of match-cards wherein the match-splints, although divided from each other for the greater portion of their length, 30 are nevertheless in contact, and support each other to aid in the preservation of the card from casual breakage.

In carrying out this invention I provide a frame, A, having suitable parallel guides, B, 35 between which the stock is fed by the rollers G. Extending through one of these guides is arranged a gang of saws, C, which, as the stock passes them, form parallel grooves in the edge of the stock, these grooves being 40 preferably of tapering form in section. As the stock passes from the saws the grooves made therein engage the gang-guide D, which consists of a number of parallel guide-strips, D', secured on the inside of the main guide, 45 so that the stock is carried in true position to the incisors E.

F is a reciprocating plate, which moves in

ways transverse to the guides B, in which are secured, usually in a suitable clamp, the gang of incisor-knives E, which project toward 50 the advancing end of the stock which is fed from the rollers. These incisors are parallel in three directions, and are arranged in the planes of the saws and of the guide-strips D'. They are short and quite thin laterally, their 55 front and rear edges being cutting-edges. They are preferably of convex form. The stock being fed down to the plate F and its incisor-knives, which reciprocate across the path between the guides or at the lower end thereof, is incised by said knives in parallel lines, 60 these incisors extending into the stock a short distance, usually about one-eighth of an inch. The incisors extend from the bottoms of the grooves of the stock toward the opposite side 65 of the same, but not entirely cutting the stock through at this side, so that the stock is left entire at said opposite side.

The plate F is also provided with a slicing bit or knife, H, the plane of which is in or 70 parallel to the plane of the reciprocating plate, and transverse to the planes of the incisors. This slicing-bit H is usually made in jawed or V form, its cutting-edges being beveled on the side away from the stock. A presser-tongue, K, is also usually provided to hold the card being cut off by the slicer. On the return of the reciprocating plate, after the parallel incisions are made in the end of the stock, the slicing-knife operates to cut off the 80 card from the end of the stock. This card passes out through an opening in the plate F, and is ready to receive the lighting 75 position.

Having described this invention, what I 85 claim, and desire to secure by Letters Patent, is—

1. The combination, with the stock-feeding guides and the grooving gang-saws, of the gang incisor-knives acting in the planes of 90 the saws and at the ends of the said guide-strips, substantially as specified.

2. The combination, with the guides for the stock and the gang of grooving-saws arranged

partially in the path thereof, of the guide-strips extending in the planes of the saws, and the transversely reciprocating-gang of incisors at the ends of said guide-strips, substantially as specified.

3. The combination, with the reciprocating plate F, of the incisors E, arranged transversely thereon, the V-shaped or jaw-shaped slicer-knife H, and the presser-tongue K, arranged beneath the said knife, the whole adapted to serve in a machine for making match-cards, substantially as shown and described.

In testimony whereof we affix our signatures in presence of two witnesses.

GILFORD FLEWWELLING.
GILBERT J. HARRIS.

Witnesses as to the signature of Gilford Flewwelling:
